UNITED STATES PATENT OFFICE.

ANDREW J. SANFORD, OF NEWARK, OHIO, ASSIGNOR TO A. H. HEISEY & CO., INCORPORATED, OF NEWARK, OHIO, A CORPORATION OF OHIO.

DESIGN FOR A GLASS DISH.

No. 38,200.

Specification for Design.

Patented Aug. 28, 1906.

Application filed July 9, 1906. Serial No. 325,419. Term of patent 7 years.

To all whom it may concern:

Be it known that I, ANDREW J. SANFORD, a citizen of the United States, residing at Newark, in the county of Licking and State of Ohio, have invented a new, original, and ornamental Design for Glass Dishes, of which the following is a specification, reference being had to the accompanying drawing, forming part thereof.

The figure is a side view of a glass dish showing my design.

What I claim is—

The ornamental design for a glass dish, as shown.

ANDREW J. SANFORD.
